COMBINED STORAGE AND DISPENSING HOLDER FOR PACKAGED ARTICLES

Thomas D. Canakes, P.O. Box 2257, Dallas, Tex.

Filed Sept. 1, 1961, Ser. No. 65,570

Term of patent 14 years

(Cl. D52—2)

FIG. 1 is a side elevation of a combined storage and dispensing holder for packaged articles showing my new design;

FIG. 2 is a front elevation thereof; and

FIG. 3 is a perspective view thereof.

The rear of the holder is substantially claimed.

I claim:

The ornamental design for a combined storage and dispensing holder for packaged articles, as shown and described.
